INVENTOR,
James L. Davidson;
BY Raymond Due-Baldrey,
ATTORNEY.

UNITED STATES PATENT OFFICE.

JAMES L. DAVIDSON, OF LOS ANGELES, CALIFORNIA.

COUNTER.

Application filed December 21, 1921. Serial No. 523,995.

To all whom it may concern:

Be it known that I, JAMES L. DAVIDSON, a citizen of the United States, residing at Los Angeles, in the county of Los Angeles and State of California, have invented new and useful Improvements in Counters, of which the following is a specification.

This invention relates to counters, and particularly to a disappearing counter top. The invention has for an object the provision of a device of this character which is economical in the use of space, and which is simple and inexpensive in construction, taken in conjunction with utility, durability and general efficiency and serviceability.

In practicing the invention, I provide a counter top having a part formed wholly or in part of unit slabs inter-connected, together and which slabs may be moved so as to leave an open space in the counter. The space immediately below the unit slabs may be utilized for various purposes, such as for an adding machine, typewriter or the like, and a device of this character will immediately be seen to be a space-saver, in that it leaves the top of the counter free for other purposes than for holding adding machines, or the like. A device of this character is particularly useful in banks, where space is at a premium, in that the adding machine may be shoved beneath the counter, and when it is desired to use the same it is unnecessary to move the machine into the room, but by simply moving the top of the counter out of position the adding machine or other device is readily accessible.

With the above and other objects in view, the invention consists in the novel and useful provision, formation, construction, combination, association and interrelation of parts, members and features, as illustrated in some of its embodiments in the accompanying drawings, described in the following detailed statement and finally pointed out in the claims.

In the drawings:

Figure 1 is a fragmentary cross sectional side view of my improved counter;

Figure 2 is a fragmentary cross sectional detail view of an arrangement for operating the slab members of the top of the counter to cause the same to disappear;

Figure 3 is a fragmentary cross sectional view of the counter top taken on the line

3—3 of Figure 4, and looking in the direction of the appended arrows; 55

Figure 4 is a fragmentary top plan view of the counter top;

Figure 5 is a fragmentary cross sectional view of certain features of the counter top 60 and its associated parts, the said view being taken on the line 5—5 of Figure 1, and looking in the direction of the appended arrows; and

Figure 6 is a front elevation of certain 65 details of construction of the improved counter top, the parts being broken away and shown in section.

Corresponding parts in all the figures are designated by the same reference characters. 70

Referring with particularity to the drawings, A includes the improved counter in its entirety, of which a is the counter top and b a back wall, and c and d other parts of the counter top, all of which elements may 75 be used in practicing one embodiment of the invention. The counter top a may be associated with the elements c and d if desired, or the elements c and d may be non-existent. Assuming, however, that the device is utilized according to the showing, the counter tops c and d which are non-movable, may be said to be of the construction ordinarily employed at the present time; and the parts c and d may carry transversely extending 80 members 1, which are likewise joined as at 2 to the back member b. Likewise joined with the members 1 and the back b are double L members 3; said members being held to the members 1 as by means of brackets 4. 85 The members 3 carry two spaced members 5 and 6. The top a bridges the gap between the members c and d, as shown in Figure 4, and the top a may be made up of a plurality of plates 7, each of which carries some filler 90 material, as 8, in the embodiment shown. Each plate 7 is united by means of hinges 9, and said hinges carry shafts 10, the ends of which shafts are received in longitudinally grooved guide-way members 11, depending 100 from and carried by the members c and d. The grooved portions of the members 11 are arranged to communicate with the members 5 and 6. The member 5 is curved as at 12 and joins with the member 11. The members 6 are each formed with a head 13 and a part 14. Each part 14 has its upper surface in alignment with the bottom of the

grooves in the member 11, with the top surface of the head portion 13 downwardly directed with respect to the top of the part 14.

It is intended that this top shall assume either a position such as illustrated in Figure 1, or that the top may be moved from said position; in other words, made to disappear. It is also intended that when the top is drawn from its disappearing position it will automatically assume the position shown in Figure 1 without any particular effort on the part of its operator. To accomplish this result one of the shafts 10 interposed between certain of the unit slabs 7 as at 15 may carry coil springs 16, the ends of which maintain the adjacent slabs 7 at the point 15 in end-to-end relation. To lower or remove the top *a* from the position shown in Figure 1 the top *a* would first be drawn outwardly so that the shaft 10 shown at 17 and carried by clips 17^a, would move a sufficient distance so the ends thereof might be directed between the head 13 and the part 12 of the member 5, whereupon the slabs would be directed downwardly with the ends of the shafts received between the members 5 and 6. This would leave a gap between the members *c* and *d* and allow a person to gain access to some machine or instrument such as shown at *e*. Moving the top *a* by grasping the angularly directed extremity 18, until the extremity reaches the position illustrated at *f* in dotted lines, would allow the last shaft 10 shown at 17 to slip from between the head 13 and the part 12 of the member 5, and the spring action existing between certain of the slabs 7 would swing the last slab 7 upwardly so that an inward push upon the end 18 would cause the shaft 10 shown at 17 to ride upon a surface, as 19, of the head 13, and from thence the said shaft would be directed to the top of the member 14, at which time all of the slabs would be in alignment.

In Figure 2 I have shown a slight modification, which consists in dispensing with the springs 16 and substituting in their stead a weighted cord member 20 joined at an end 21 of the last slab. The cord passes over a sheave or pulley 23 carried by the part 14, and a weight 22 connected with the cord at all times exerts an upward pull on the last slab 7, so that the result accomplished is the same as by the spring 16.

Various refinements of detail may be resorted to, and it is only intended that the drawings show one embodiment of the invention, and how it may be carried into practice.

It is obvious many changes and variations and modifications may be made in departure from the particular description and showing of the accompanying drawings, in adapting the invention to varying conditions and requirements of use and service,

without departing from the true spirit of the invention.

Having thus disclosed my invention, I claim and desire to secure by Letters Patent:

1. A store counter comprising in combination, fixed counter portions and an intermediate disappearing counter section, and intersecting communicating horizontal and upright guideways, the horizontal guideway of which extends across the upright guideway, and means within the guideways having means whereby said disappearing counter section may be moved into the plane of the fixed counter portions to provide a movable counter section coextensive with the transverse dimension of said fixed counter portions.

2. A store counter unit adapted to assume either a horizontal position or a position at an angle to the horizontal, said unit comprising means forming an upright guideway and a horizontal guideway communicating with each other, and said horizontal guideway extending to opposite sides of the plane of the upright guideway, a shiftable top portion comprising a plurality of pivotally connected sections having means engaging in said guideways whereby said sections may be moved from the upright guideway into the horizontal guideway and then be shifted rearwardly across the upright guideway to provide a full width top portion.

3. A store counter unit adapted to assume either a horizontal position or a position at an angle to the horizontal, said unit comprising means forming an upright guideway and a horizontal guideway communicating with each other, said horizontal guideway extending to opposite sides to the plane of the upright guideway, and means arranged at the junction of said upright and horizontal guideways for providing a top directing part and also providing an offset continuation of said horizontal guideway, and a sectional top including slab members and rods pivotally connecting the slabs, said rods adapted to travel in said guideways, whereby said sections may be moved from the upright guideway into the horizontal guideway and then be shifted rearwardly across the upright guideway to provide a full width top portion.

4. A store counter comprising relatively fixed top portions and an intermediate disappearing top portion, said disappearing top portion comprising a plurality of hingedly connected slab members, a guideway formed in the plane of the fixed top members and extending the full width thereof, and another guideway disposed at an angle to said first named guideway and communicating with the latter between the ends thereof, means at the junction of said guideways for guiding the slidable top section

into the end of said horizontal guideway opposite to the direction of major movement of the sliding top, and means for automatically lifting the rear slab member whereby 5 its guide engaging portion is lifted out of the upright guideway and into the horizontal guideway, whereby said sections may be moved from the upright guideway into the horizontal guideway and then be shifted 10 rearwardly across the upright guideway to provide a full width top portion.

5. A store counter comprising relatively fixed top portions and an intermediate disappearing top portion, said disappearing top portion comprising a plurality of hingedly connected slab members, means in the 15 plane of the fixed top sections forming a

guideway coextensive with the width thereof, guide forming means disposed at an angle to said horizontal guideway and communicating therewith between the ends thereof, and a deflector located at the junction of said guideways and adapted to direct one edge portion of said disappearing top into the adjacent end of the horizontal 20 guideway, whereby said sections may be moved from the upright guideway into the horizontal guideway and then be shifted rearwardly across the upright guideway to 25 provide a full width top portion. 30

In testimony whereof, I have signed my name to this specification.

JAMES L. DAVIDSON.
